UNITED STATES PATENT OFFICE

156,949

COMBINED CIGARETTE CASE AND LIGHTER

Mack Forman, Providence, R. I., assignor to Marathon Company, a corporation of Massachusetts

Application May 12, 1949, Serial No. 2,609

Term of patent 14 years

(Cl. D48—27)

To all whom it may concern:

Be it known that I, Mack Forman, a citizen of the United States of America, residing at Providence, county of Providence, State of Rhode Island, have invented a new, original, and ornamental Design for a Combined Cigarette Case and Lighter, of which the following is a specification, reference being had to the accompanying drawing, forming a part thereof.

Fig. 1 is a top plan view of a combined cigarette case and lighter showing my new design;

Fig. 2 is a side elevation thereof; and

Fig. 3 is a perspective view thereof.

The characteristic features of my new design reside in those portions shown by means of full lines in the drawing.

I claim:

The ornamental design for a combined cigarette case and lighter, substantially as shown and described.

MACK FORMAN.
